UNITED STATES PATENT OFFICE

151,212

DESIGN FOR AN ENGRAVING MACHINE

Philip J. Brohawn, New York, N. Y., assignor to
International Engraving Machine Corp., a cor-
poration of New York

Application September 28, 1946, Serial No. 133,816

Term of patent 3½ years

(Cl. D64—11)

To all whom it may concern:

Be it known that I, Philip J. Brohawn, a citizen of the United States of America and a resident of the city of New York, in the county of Queens and State of New York, have invented a new, original, and ornamental Design for an Engraving Machine, of which the following is a specification, reference being had to the accompanying drawing, forming a part thereof.

The figure is a perspective view of an engraving machine, showing my design.

I claim:

The ornamental design for an engraving machine, substantially as shown.

PHILIP J. BROHAWN.
